UNITED STATES PATENT OFFICE.

ANTONI BRZYKCY, OF MINNEAPOLIS, MINNESOTA.

WINDMILL.

Application filed December 8, 1921. Serial No. 520,853.

To all whom it may concern:

Be it known that I, ANTONI BRZYKCY, a citizen of the United States, residing at Minneapolis, in the county of Hennepin and 5 State of Minnesota, have invented certain new and useful Improvements in Windmills; and I do hereby declare the following to be a full, clear, and exact description of the invention, such as will enable others 10 skilled in the art to which it appertains to make and use the same.

My present invention relates to windmills, and more particularly, to power transmission mechanism therefor.

15 Such transmission mechanism which includes an upright shaft connected, by gears, to the wind wheel shaft and having its axis at the axis of the rotary head on which the wind wheel shaft is journaled, is objectionable for the reason that the driving torque transmitted through the upright tends to rotate the head in the direction of the rotation of the upright shaft, and, hence, tends to move the wind wheel out 25 of the wind. The object of my invention is to eliminate this objection by providing a transmission mechanism having a belt drive.

To the above end, generally stated, the 30 invention consists of the novel devices and combinations of devices, hereinafter described and defined in the claims.

In the accompanying drawings which illustrate the invention, like characters indicate like parts throughout the several 35 views.

Referring to the drawings:—

Fig. 1 is a view principally in elevation with some parts sectioned, showing a windmill having one form of the invention embodied therein;

Fig. 2 is a view partly in plan and partly in horizontal section, taken on the line 2—2 of Fig. 1;

45 Fig. 3 is a fragmentary view, partly in plan and partly in section, taken on the line 3—3 of Fig. 1;

Fig. 4 is a fragmentary detail view, partly in elevation and partly in central 50 vertical section;

Fig. 5 is a fragmentary detail view with some parts sectioned on the line 5—5 of Fig. 4;

55 Fig. 6 is a view corresponding to Fig. 4, but showing another form of the invention; and

Fig. 7 is a detail view with some parts sectioned on the line 7—7 of Fig. 6.

Referring first to the invention shown in Figs. 1 to 5 inclusive, the numeral 8 indicates a windmill tower of the usual construction and has, at its top, a turntable 9. A platform 10 and a cross timber 11 are secured to the tower 8 below the turntable 9, and the latter below the former. A vane 12 is carried by the shank 13 having, at its inner end, a large hub 14 supported on anti-friction devices 15 from the turntable 9.

On the under side of the head 16 is a 70 bearing sleeve 17 rotatably mounted on the hub 14, and which head is rigidly secured to the upper end of the tubular shaft 18 which extends through said sleeve and head, and a bracket 19 secured to the upper face of the hub 14. The shaft 18 extends centrally within the tower 8 and is rotatably mounted in the turntable 9 and platform 10 and also in the hub 14 which is free to rotate in respect thereto.

80 A wind wheel 20, of the usual or any desired construction, is keyed to one end of a horizontal shaft 21 journaled in a pair of aligned bearings 22 formed with the bracket 19 and located on diametrically opposite sides of the shaft 18. Axially aligned with the shaft 18 and endwise spaced therebelow, is a shaft 23, the upper end of which is journaled in a bearing block 24 and the lower end of which is journaled in a bearing 25 in the cross timber 11. The bearing block 24 is rigidly secured to the shaft 18 for rotation therewith, by a pair of depending bars 26, the upper ends of which are bolted to the outer sides of the lower end portion of the shaft 18 at diametrically opposite points and the lower ends of said bars are bolted to the bearing block 24 which extends therebetween.

90 The shaft 23 is driven from the wind wheel shaft 21 by a belt drive which comprises an upper section 27 and a lower section 28, both of which are in the form of chains. The upper section 27 of the belt drive is arranged to run over a chain wheel 29 on the shaft 21 and a chain wheel 30 on a short shaft 31 journaled in the bars 26. The lower belt section 28 is arranged to run over a chain wheel 32 on the shaft 31 outward of the bars 26 and a chain wheel 33 on the upper end of the shaft 23. The lower section 28 of the belt drive also runs over

idle wheels 34 journaled in an outstanding lug 24' on the bearing block 24. A counter-shaft 35 is journaled in bearings 36 on the tower 8 and driven from the shaft 23 by a belt 37 which runs over a grooved wheel 38 on the shaft 23 and a grooved wheel 39 on the countershaft 35. The belt 37 also runs over a guide sheave 40 on the cross timber 11. Keyed to the countershaft 35 is a plurality of pulleys 41, over which run, belts 42 for driving various different kinds of machines or devices, not shown.

Obviously, the wind wheel 20 is free to swing in a horizontal plane in respect to the vane 12 and to limit the swinging movement to substantially ninety degrees, there is provided a link 43 which permits the wind wheel 20 to swing from a position "in the wind" or at right angles to the vane, to a position "out of the wind," or substantially parallel to said vane. This link 43 is secured to the hub 14 by a headed pin 44, and to an annular collar 45 on the bearing sleeve 17 by a pivot bolt 46, and is free for, both, pivotal and sliding movement on said pin and bolt.

To remove the wind wheel 20 from one extreme position to the other, there is provided a horizontal shaft 47 journaled in bearings 48, one of which is secured to a bracket 49 on the hub 14 and the other is secured to the shank 13. On one end of the shaft 47, is a worm 50 which meshes with a segmental worm gear 51 on the periphery of the collar 45. A chain wheel 52 is keyed to the other end of the shaft 47, and over which runs an endless operating chain 53. This operating chain 53 extends nearly to the ground so that the same may be easily reached by an operator, and by drawing on either side of said chain, the shaft 47 may be rotated to move the wind wheel from one extreme position to the other. The worm 50 and worm gear 51 act as a lock tending to hold the wind wheel 20, where set. A brace 54, attached to the bearing sleeve 17 by a collar 55 and to the outer end of the shank 13, is provided to support said outer end of the shank. On the extreme lower end of the shaft 23 is a bevel gear 56, from which, may be driven, a machine or other device.

Referring now to the invention as illustrated in Figs. 7 and 8, there is provided a single belt 57 for driving the shaft 23 from the shaft 21, in place of the two-section belt drive illustrated in Figs. 1 to 5, inclusive. This belt 57 runs over a grooved wheel 58 on the shaft 51 and a grooved wheel 59 on the shaft 23. To direct the belt 57 from a position in which it travels in a vertical plane over the wheels 58 to a horizontal position in which it travels over the wheel 59, the same is caused to run over pairs of upper and lower idle grooved wheels 60 and 61, respectively, the former of which is journaled on

the bearing block 24 and the latter of which is journaled on the lug 24'.

What I claim is:

1. In a windmill, the combination with a rotatable head, of a wind wheel having a shaft journaled on the head, a shaft secured for rotation with the head, a driving shaft, wheels on the wind wheel shaft and the driving shaft, a belt drive arranged to run over said wheels, and means carried by the shaft secured to the head for changing the direction of travel of the belt drive. 70

2. In a windmill, the combination with a rotatable head, of a wind wheel having a shaft journaled on the head, a tubular shaft 80 secured for rotation with the head, a driving shaft, wheels on the wind wheel shaft and the driving shaft, a belt drive arranged to run over said two wheels and through said tubular shaft, and guide sheaves carried by the tubular shaft for changing the direction of travel of the belt drive. 85

3. In a windmill, the combination with a rotatable head, of a wind wheel having a shaft journaled on the head, a tubular shaft 90 secured for rotation with the head, a driving shaft axially aligned with the tubular shaft, wheels on the wind wheel shaft and the driving shaft, a belt drive arranged to run over said two wheels and through said 95 tubular shaft, a bearing block secured to the tubular shaft, and guide sheaves on the bearing block for changing the direction of travel of the belt drive.

4. In a windmill, the combination with a 100 rotatable head, of a wind wheel having a shaft journaled on the head, a tubular shaft secured for rotation with the head, a bearing block secured to the tubular shaft, a driving shaft axially aligned with the tubular shaft and journaled in the bearing block, wheels on the wind wheel shaft and the driving shaft, a belt drive arranged to run over said two wheels and through said tubular shaft, and guide sheaves on the bearing 105 block for changing the direction of travel of the belt drive. 110

5. In a windmill, the combination with a rotatable head, of a wind wheel having a shaft journaled on the head, a tubular shaft secured for rotation with the head, a driving shaft, wheels on the wind wheel shaft and the driving shaft, a pair of connected wheels journaled on the tubular shaft, a belt drive comprising upper and lower sections, said upper section being arranged to run over one of said connected wheels and the wheel on the wind wheel shaft and said lower section being arranged to run over the other of said connected wheels and the 115 wheel on the driving shaft, and means carried by the tubular shaft for changing the direction of travel of the lower section of the belt drive. 120

6. In a windmill, the combination with a 120

rotatable head, of a wind wheel having a shaft journaled on the head, a tubular shaft secured for rotation with the head, a bearing head carried by the tubular shaft, a driving shaft journaled on the bearing block, wheels on the wind wheel shaft and the driving shaft, a pair of connected wheels journaled on the tubular shaft, a belt drive comprising upper and lower sections, said upper section being arranged to run over one of said connected wheels and the wheel on the wind wheel shaft and said lower section being arranged to run over the other of said connected wheels and the wheel on the driving shaft, and guide sheaves journaled on the bearing block for changing the direction of travel of the lower section of the belt drive.

7. In a windmill, the combination with a rotatable head, of a wind wheel having a shaft journaled on the head, an upright tubular shaft secured at its upper end to the head for rotation therewith, a pair of de-

pending bars having their upper ends secured to the lower end of the tubular shaft at diametrically opposite points, a bearing block secured to and between the lower ends of said bars, a driving shaft axially aligned with the tubular shaft and journaled in the bearing block, wheels on the wind wheel shaft and the driving shaft, a pair of connected wheels journaled on said bars, a belt drive comprising upper and lower sections, said upper section being arranged to run over one of said connected wheels and the wheel on the wind wheel shaft and said lower section being arranged to run over the other of said connected wheels and the wheel on the driving shaft, and guide sheaves journaled on the bearing block for changing the direction of travel of the lower section of the belt drive.

In testimony whereof I affix my signature.

ANTONI BRZYKCY.
